UNITED STATES PATENT OFFICE.

OWEN E. KENNEY, OF TOLEDO, OHIO, ASSIGNOR TO THE YOST ELECTRIC MANUFACTURING COMPANY, OF TOLEDO, OHIO, A CORPORATION OF OHIO.

SEPARABLE ATTACHMENT-PLUG.

No. 884,981.

Specification of Letters Patent. Patented April 14, 1908.

Application filed March 16, 1906. Serial No. 306,352.

To all whom it may concern:

Be it known that I, OWEN E. KENNEY, a citizen of the United States, and a resident of Toledo, in the county of Lucas and State of Ohio, have invented certain new and useful Improvements in Separable Attachment-Plugs; and I do hereby declare the following to be a full, clear, and exact description of the invention, such as will enable others skilled in the art to which it appertains to make and use the same, reference being had to the accompanying drawing, and to the figures of reference marked thereon, which form a part of this specification.

15 My invention relates to separable attachment-plugs adapted for use in making a quick and effective connection between movable electric appliances such as lights, fans, motors, heating apparatus, surgical instruments, or the like, and fixtures disposed in an electric circuit; and it has for its object the provision of an improved attachment-plug of this class which is of efficient, economical and simple construction, and had its separable parts so interlocked as to permit an easy and quick separation or connection thereof.

To these ends my invention consists of certain novel features of construction, combination and arrangement of the parts, which are 30 hereinafter fully described, and illustrated in the accompanying drawings, in which,—

Figure 1 is a central vertical section of an attachment-plug comprising the features of my invention, the same being taken on the line x' in Fig. 2. Fig. 2 is a plan view of the inner side of the cap with the base removed. Fig. 3 is a cross-section of the cap taken on the line $x-x$ in Fig. 2, and Fig. 4 is a plan view of the inner end of the base with the cap removed and a portion of one of the spring contact arms broken away.

Referring to the drawings, 1 represents the base of the plug which is made of porcelain, fiber or other suitable insulating material 45 and formed on its inner face with a cavity 2 and on its outer face or end with a central integral stem 3 of like material, which base and stem are provided with a central hole 4 extending entirely therethrough and adapted 50 for the insertion of a contact post or screw 5.

Within the cavity 2 of the base are formed the two radially-disposed longitudinally-aligning grooves 6 and 7, the former of which is the longer and has its inner end extending

across the hole 4 of the base. Mounted within these grooves are the two U-shaped contact-terminals 8 and 9, which are secured in relatively fixed positions by the screws 10 and 11, respectively, which pass through apertures in the base 1 and have their heads disposed in the sockets 12 and 13, provided in the sides of the stems 3 for their reception. These sockets are formed by the provision of semi-circular grooves in the opposite sides of the stem 3, the outer or open sides of which are closed by a metallic screw-shell or sleeve 14, which encircles the stem 3 but leaves the outer end thereof exposed, as shown in Fig. 1.

The terminals 8 and 9 are reversely disposed so that their outer or free ends form inwardly-projecting spring-arms, which are of substantially equal length and formed with indentures or grooves 15 for the purpose hereinafter described. The inner or fixed end of the terminal 8 is made of suitable length to cross the hole 4 and engage with the inner end of the contact-post or screw 5, it being provided with a threaded aperture for that purpose. The terminal 9 has conductive connection with the shell or sleeve 14, 80 due to the passing of the screw 11 through an aperture in the metallic bracket 16 secured to said shell or sleeve; and the screw 10, which secures the terminal 8 to the base, is insulated from said shell or sleeve by insulating cement, which is deposited in the socket 12 on top of the screw-head, as at 17, thus preventing a short-circuiting of the current. A removal of this cement from the top of the screw may be effected by the insertion 90 of a suitable loosening instrument within the cut-away portion 14^a at the base of said shell or sleeve.

18 represents a cap which is made of porcelain or other suitable nonconducting or insulating material and formed with a central opening or passage 19 through which pass the wires 20 and 21, leading to the lamp, fan or other attached apparatus, said passage being enlarged at its inner portion for the reception 100 of a suitable knot made in the lead-wires to prevent their withdrawal from the cap should they become loosened from their binding-posts.

The inner portion of the cap is formed with a circular cavity having the deeper segmental recesses 22, 22, within which are mounted the binding-post plates 23 and 24, each carry-

ing at one end a binding-screw 25, and being secured to the cap by the screws 26. The ends of the plates opposite to those carrying the screws 25 are returned to constitute 5 spring-arms, which overlap the ends of the securing screws 26 and are formed with small teats 27 to adapt them to interlock with the indentures or grooves 15 in the terminals 8 and 9.

10 When the base 1 is screwed into a socket upon the wall, ceiling or floor so that the exposed or outer end of the contact-post or screw 5 and the screw shell or sleeve 14 have contact with the proper terminals of the main- 15 circuit wires leading to said sockets, the circuit may be completed to the fan, motor or lamp by placing the cap 18, having the circuit wires 20 and 21 attached to the respective contact-plates 23 and 24 by the binding- 20 screws 25, upon the rim of the base and turning it until the spring-arms of the contact- plates 23 and 24 travel under the spring- arms of the terminals 8 and 9 and their corresponding indentures or grooves interlock, 25 thus preventing an accidental disengagement of the two parts of the plug.

28, 28 are lugs extending slightly beyond the rim of the cap to aid in guiding the cap when it is being turned into its seat in the 30 base.

29 represents an insulating strip or shield, which is disposed over the spring-contact terminals 8 and 9 of the base to act as a protection to the person screwing the plug into the 35 socket. This strip is secured to the base by having its ends bent at right angles to its major portion and inserted between the looped ends of said terminals and the wall of the base cavity 2.

40 It will be obvious that my construction provides a simple and improved form of separable attachment plug, which has its parts so assembled that danger of short-circuiting is reduced to a minimum, and which is adapted 45 to have its cap and base easily and quickly engaged or disengaged for the purpose of making or breaking a circuit with the attached apparatus.

Having thus described my invention, what

I claim as new and desire to secure by Let- 50 ters Patent, is,—

1. A separable attachment-plug, comprising a base of insulating material having a recessed end and provided therein with oppositely-disposed contact terminals having inwardly-projecting spring-arms, 55 a cap of insulating material having a recessed end and a passage for lead-wires and having spring- contact arms adapted to interlock with the terminals of the base, and an insulating 60 shield or member disposed transversely of the recessed portion of the base and over the terminals therein with its ends bent and inserted between the outer ends of said terminals and the wall of the recess, substantially 65 as described and for the purpose specified.

2. A separable attachment-plug comprising a base of insulating material having a recessed end and provided with a central aperture and side apertures, screws passed 70 through each of said apertures, oppositely- disposed U-shaped contact terminals secured within the recess by the screws passing through said side apertures, said terminals having their arms disposed inwardly and one 75 having its inner arm prolonged and engaged by the screw in the central aperture, an insulating shield disposed over the contact terminals, a cap of insulating material having a central lead-wire passage and a recessed end 80 provided in its bottom with opposite seg- mental recesses, binding-post plates secured within said segmental recesses by screws and each having an end turned back to form a contact terminal for passing to the rear of and 85 locking with the free arm of one of the base terminals whereby to retain the base and cap together and form a circuit, said insulating shield being prevented from removal by the clamping together of the cap and base, sub- 90 stantially as and for the purpose described.

In testimony whereof, I have hereunto signed this specification in the presence of two subscribing witnesses.

OWEN E. KENNEY.
